HYDRAULIC PUMPING SYSTEM

Roy B. Bryant, Dallas, Tex.

Application February 23, 1933, Serial No. 658,019

7 Claims. (Cl. 103—46)

This invention relates to new and useful improvements in hydraulic pumping systems.

One object of the invention is to provide an improved hydraulic pumping system for oil and water wells and particularly for deep wells.

An important object of the invention is to provide a pumping apparatus in which the elements may be arranged one within the other and lowered into the casing.

Another object of the invention is to provide a controlling apparatus on the surface, whereby the pumping operation of one or more wells may be controlled.

A particular object of the invention is to provide an improved pumping apparatus of the balanced pressure type, but in which a comparatively small number of parts are required and in which the operation will be simple and positive.

A construction designed to carry out the invention will be hereinafter described, together with other features of the invention.

The invention will be more readily understood from a reading of the following specification and by reference to the accompanying drawings in which an example of the invention is shown, and wherein:

Figure 1 is an elevation of a pumping apparatus constructed in accordance with the invention.

Figure 2 is a vertical sectional view of the same, in position in the casing.

Figure 3 is an elevation of the operating and controlling mechanism, and

Figures 4 and 5 are diagrammatical views of the control valve.

In the drawings the numeral 1 designates a lower pump cylinder and 2 an enlarged upper pump cylinder, preferably integral with the lower cylinder. A tubular piston 3 has a snug sliding fit in the lower cylinder and carries at its upper end an enlarged tubular piston 4 having a snug sliding fit in the cylinder 2. These pistons are connected so as to move in unison. A section of tubing is mounted axially in the cylinders and the pistons and is provided with a reduced screw-threaded nipple 14 at its lower end, which is screwed through the bottom of the cylinder 1. The outer surface of the tubing is machined so that the pistons 3 and 4 have a snug sliding fit thereon. The cylinder 2 is provided with external lugs 13, which act to center the cylinders in the casing 12.

A valve sleeve 36 is mounted in the lower portion of the tubing 5 and rests upon a packing gasket 38. The upper end of the sleeve is packed off by a packing 37 engaging the tubing. This leaves an annular vertical space between the sleeve and the tubing. It is also pointed out that annular vertical spaces are provided between the pistons 3 and 4 and the tubing. A valve 10 is seated in the lower end of the sleeve and a

spring-pressed valve 11 is seated in the sleeve a substantial distance above the valve 10. Ports 6 in the tubing permit fluid to flow from the cylinder 1 into the space between the tubing and the valve sleeve. There are two sets of ports 6, and the upper set is placed opposite ports 7 in the valve sleeve above the valve 10 and below the valve 11. When fluid enters through the nipple 14 and unseats the valve 10, which is of the wing type, said fluid may flow out through the ports 7 into the space between the sleeve and the piston and then escape through the ports 6 into the cylinder 1. The spring-pressed valve 11 will remain closed.

The wall of the piston 4 is made sufficiently thick to form a weight 17, which is supported on a coiled spring 34 resting on the bottom of the cylinder 2. Ports 8 in the tubing are normally opposite ports 9 in the upper end of the piston 3. Assuming the pistons 3 and 4 to be elevated and unrestrained, it is obvious that the weight 17 will force the same downwardly and the spring 34 will cushion this drop. When the pistons move downwardly liquid will be forced from the cylinder 1 through the ports 6 and 7 into the sleeve 36. The valve 10 will, of course, be held to its seat, but the valve 11 will be lifted and the liquid elevated past said valve through the sleeve 36 into the tubing 5. Liquid in the cylinder 2 will be forced through the ports 8 and 9 into the tubing 5. When pressure is applied to the fluid in the tubing 5, the valve 11 will be seated, thus causing the liquid to flow through the ports 8 and 9 under pressure and elevate the pistons, whereby suction will be created in the cylinder 1 and liquid drawn thereinto in the manner previously described.

In Figure 3 I have shown the controlling and operating means, which includes a pump 18 driven by a motor 19. The pump is of the reciprocating type and has a pinion 20 on its shaft, driving a gear 21, which is provided with a cam track or groove 28. A lever 23, pivoted at its lower end to the base of the apparatus, has a roller 22 intermediate its ends engaging in the cam track. A link 24 connects the upper end of the lever with the arm 25 of a control valve 16. It is obvious that as the gear 21 is revolved, the cam will swing the lever 23, whereby the arm 25 will shift the valve gate 29 from the position shown in Figure 4 to the position shown in Figure 5 and vice versa.

The valve is provided with a connection 30 leading into a tank 15, which has an overflow discharge 31 leading to the storage tanks or other point. The valve has two outlets, one marked No. 1 and the other marked No. 2. These outlets are connected with the tubing 5 in No. 1 well and the tubing 5 in a No. 2 well. In the position shown in Figure 5, liquid is free to flow through the outlet No. 1 to the tank 15. When

the valve is shifted to the position shown in Figure 4, No. 1 well is cut off from the tank, but liquid is free to flow through the outlet No. 2 to the tank from the No. 2 well. The stem 16' of the 5 valve is connected by a pipe 27 with the pump 18 and the pump 18 is connected with the tank by a suction pipe 26.

In operating the system, the pump 18 is continuously acting and by connecting two wells 10 there is no idle pumping period. It will be assumed that all pipes and parts are full of liquid and the valve gate 29 is in the position shown in Figure 4. The pump 18 will be forcing liquid from the tank 15 through the pipe 27 to the outlet 15 No. 1 and thence into the tubing 5 of No. 1 well. This fluid passes through the ports 8 and 9 and acting against the piston 4, elevates said piston, together with the piston 3. The piston 3 thus goes through its suction stroke, whereby 20 liquid is drawn in through the inlet 14 past the valve 19 into the sleeve 36 and thence through the ports 6 and 7 into the cylinder 1.

While the pump 18 is forcing liquid into No. 1 well, the weight 17 in No. 2 well is descending, 25 whereby liquid is being forced from the cylinder 1 through the ports 6 and 7 and past the valve 11 and thereby being elevated in the tubing 5. This liquid is entering the valve 16 through the No. 2 outlet (Figure 4), from which it flows 30 through the connection 30 to the tank 15. Once during each revolution of the gear 21, the lever 23 is shifted so that during substantially one-half of the revolution of said gear the gate 29 is in the position shown in Figure 4 and during the 35 remaining half of the revolution said gate is in the position shown in Figure 5. Therefore, during one-half of the revolution of said gear the pump 18 is forcing liquid into the tubing of one well and during the remaining half it is forcing liquid into the other well. When liquid 40 is being forced into one well the weight 17 in the other well is causing a discharge of liquid therefrom, as will be obvious.

It is pointed out that each outlet No. 1 and 45 No. 2 could be connected to several wells and any one of these wells could be cut off when it was not desired to pump the same. When the weight 17 descends, considerable momentum will be given to the discharging column of fluid and this will cause the flow to continue for a brief 50 period. The pump 18 merely has to elevate the weight 17 and as the same is balanced against the column of fluid, it is obvious that a small high-speed pump is all that is necessary.

The description which has been given recites 55 more or less detail of a particular embodiment of the invention, which is set forth as new and useful; however, I desire it understood that the invention is not limited to such exact details of construction, because it is manifest that changes and modifications may be made within the scope 60 of the appended claims, without departing from the spirit of the invention.

What I claim and desire to secure by Letters 65 Patent, is:

1. A hydraulic pumping system comprising, a pumping cylinder adapted to be lowered into a well, a piston operating in said cylinder, a stationary tubing in said piston, the tubing communicating with the cylinder through the piston and below the piston, valves within the tubing, and means carried by the piston for forcing the

same downwardly to displace liquid from the cylinder into the tubing and also to discharge it from the tubing.

2. A hydraulic pumping system comprising, a pumping cylinder adapted to be lowered into a well, a piston operating in said cylinder, a stationary tubing in said piston, the tubing communicating with the cylinder through the piston and below the piston, valves within the tubing, means carried by the piston for forcing the same 5 downwardly to displace liquid from the cylinder into the tubing and also to discharge it from the tubing, and means for elevating the piston to draw liquid into the tubing and cylinder.

3. A hydraulic pumping system comprising, a cylinder adapted to be lowered into a well, a tubing extending longitudinally in the cylinder and having an inlet at its lower end, a piston surrounding the tubing in the cylinder, the tubing and piston having liquid passage ports communicating with the cylinder through the piston and below said piston, a valve in the tubing, and a weight on the piston for depressing it.

4. A hydraulic pumping system comprising, a cylinder adapted to be lowered into a well, a tubing extending longitudinally in the cylinder and having an inlet at its lower end, a piston surrounding the tubing in the cylinder, the tubing and piston having liquid passage ports communicating with the cylinder through the piston and below said piston, a valve in the tubing, a weight on the piston for depressing it, and a spring in the cylinder cushioning the weight.

5. A hydraulic pumping system comprising, a cylinder adapted to be lowered into a well, a tubing extending longitudinally in the cylinder and having an inlet at its lower end, a piston surrounding the tubing in the cylinder, the tubing and piston having liquid passage ports communicating with the cylinder through the piston and below said piston, an inlet valve in the tubing, and an outlet valve in the tubing between said ports, and means carried by the piston for depressing it.

6. A hydraulic pumping system comprising, a cylinder adapted to be lowered into a well, a tubing extending longitudinally in the cylinder and having an inlet at its lower end, a piston surrounding the tubing in the cylinder, the tubing and piston having liquid passage ports, a sleeve in the tubing, an inlet valve mounted at the lower end of the sleeve, an outlet valve mounted in the sleeve, the sleeve and tubing having liquid passage ports between the valves, and weight means for depressing the piston.

7. A hydraulic pumping system comprising, a pumping cylinder adapted to be lowered into a well, a piston operating in said cylinder, a stationary tubing in said piston, the tubing communicating with the cylinder through the piston and below the piston, valves within the tubing, means carried by the piston for forcing the same downwardly to displace liquid from the cylinder into the tubing and also to discharge it from the tubing, a tubing connected with the cylinder and piston, a controlling valve connected with the tubing, a pump connected with the valve, and automatic means for shifting the controlling valve to disconnect the pump with the tubing to open said tubing to discharge.

ROY B. BRYANT.
